UNITED STATES PATENT OFFICE.

LEE DE FOREST, OF PALO ALTO, CALIFORNIA, ASSIGNOR TO RADIO TELEPHONE & TELEGRAPH COMPANY, A CORPORATION OF DELAWARE.

MEANS FOR INCREASING THE STRENGTH OF ELECTRIC CURRENTS.

1,134,594.

Specification of Letters Patent.

Patented Apr. 6, 1915.

Application filed April 11, 1912. Serial No. 690,113.

To all whom it may concern:

Be it known that I, LEE DE FOREST, a citizen of the United States, residing at Palo Alto, in the county of Santa Clara, State of California, have made a certain new and useful Invention in Means for Increasing the Strength of Electrical Currents, of which the following is a specification.

10 This invention relates to improvements in means for transmitting sounds, signals or human intelligence by means of electric currents either through conducting wires, or by the radiation of electro-magnetic waves, 15 and particularly, to means employed for boosting or increasing the strength of the transmitted signaling current.

The object of the invention is to provide means for increasing the intensity of 20 telegraphic or telephonic received signals transmitted with or without the use of line conductors.

Other objects of the invention will appear more fully hereinafter.

25 The invention consists substantially in the construction, combination, location and arrangement, all as will be more fully herein-after set forth, as shown in the accompanying drawings, and finally pointed out in the 30 appended claim.

Referring to the accompanying drawings, and to the various views and reference signs appearing thereon,—Figure 1 is a view, somewhat diagrammatic, showing one form 35 of construction, embodying my invention wherein a homo-polar dynamo is employed to effect the increased intensity of the received signal currents. Fig. 2 is a similar view in top plan.

40 The same reference sign occurs throughout the several views to designate the same part.

In accordance with the principles of my present invention, I propose to relatively 45 move a closed conductor and coils suitably connected up and through which the currents to be amplified are conducted, and which coils are associated with a receiving apparatus. The relative movement of the 50 closed conductor and the coils associated therewith, in the attainment of the objects and purposes of my invention, may be accomplished in any suitable or convenient manner, and in many different ways. Ordinarily I provide a motor-driven means for

dynamically amplifying the minute received current impulses imparting thereto new energy from a local source without moving contacts, microphonic or otherwise, or without ohmic resistances, or resistance altering 60 devices.

In accordance with my invention the intensity or amplitude of the received current impulses is increased without however varying essentially, or distorting, the wave-form characteristic of the received impulses.

65 In Fig. 1, I have shown one arrangement embodying my invention wherein I employ magnets E^1 which are placed with their axis, or the axis of their cores, perpendicular to the plane of the conducting disk I^2 . The currents to be intensified or amplified are conducted through windings or coils placed upon the legs of the cores E^1 . Three 70 of these magnet E^1 , are shown, each of which carries two separate windings P^2 , S^2 , 75 constituting, respectively, the primary and secondary coils of a transformer, the secondary winding of one set being connected to the primary coil of the next adjacent set 80 or magnet, and so on. If desired, of course, all of the coils may be connected up in series, and with the telephone receiver T^2 . In either case there will take place three successive amplifications. I find that this am- 85 plifying process can be carried on almost indefinitely so that extremely weak or in- audible signal pulsations or currents may be made very strong and the sound pro- 90 duced, or the work accomplished thereby, increased. This is particularly so with such signals as are used in wireless telegraphy where it is of little consequence if the exact tone qualities of the received impulses 95 are somewhat distorted, volume of sound being here the chief consideration. But with voice transmission the distortion ob- 100 served with two or three successive amplifications such as I have described is incon- siderable.

In the construction shown in Fig. 1 the conductor I^2 , may be rotated in any suitable or convenient manner, or the relative rotation or movement of said closed conductor and the cores of magnets E^1 may be ac- 105 complished in many suitable or different ways. I have shown the conductor disk I^2 , as driven from a motor M^2 , for axial ro- 110 tation of the former.

In Fig. 2 I have shown diagrammatically

an arrangement wherein two successive amplifications of the received current impulses are accomplished. In this arrangement a conductor or closed conductor I^3 , is employed. The relative movement of the closed conductor and the magnet cores or coils is accomplished by suitably rotating axially the conductor disk I^3 . In this arrangement two magnet cores E^3 , are employed which constitute cores for coils P^3 , S^3 . Two coils P^3 , S^3 , being associated with each core E^3 . The magnets are arranged with their pole ends presented toward and in close proximity to the side surfaces of the conductor I^3 . One of the coils as P^3 , receives initially the transmitted current impulses. The coil S^3 associated with the initially current impulse receiving coil P^3 , is in series with the coil P^3 of the second amplifier. The final amplification of current impulses are received in the telephone T^3 . Care should be taken in the design of such an amplifying homo polar generator as I have described, to reduce all but the useful eddy currents and all iron losses as far as possible, by proper lamination of the stator and rotor bodies. For example, the stator S^3 , may be built up of soft iron punchings, the planes of which pass through the axis of rotation of the machine. Similarly, the rotor body can be of the form of a squirrel cage armature. Similarly, the laminated rings of the inner coil L^3 , should not be com-

plete circles but this ring should be cut in two, leaving a small air gap therein.

35

Having now set forth the object and nature of my invention, and various forms and constructions of arrangement of apparatus for accomplishing the same, and having explained the purposes, functions, and mode of operation of the various arrangements shown and described, what I claim as new and useful, and of my own invention, and desire to secure by Letters Patent of the United States, is,—

45

In an apparatus for amplifying feeble electric currents or current impulses, a transformer having its primary coil in circuit with the source of current to be amplified, its secondary coil connected with the primary of a second transformer, the secondary of the second transformer connected with a signal indicating device, and a conductor disposed with relation to both of said transformers to cut the magnetic lines of force thereof, and means for relatively moving said conductor transversely to the magnetic lines of force.

55

In testimony whereof I have hereunto set my hand in the presence of the subscribing witnesses, on this 26th day of March A. D., 1912.
